UNITED STATES PATENT OFFICE.

WILLIAM R. McCULLA, OF DETROIT, MICHIGAN, ASSIGNEE TO FORD MOTOR COMPANY, OF DETROIT, MICHIGAN, A CORPORATION OF MICHIGAN.

MUFFLER.

1,140,693.

Specification of Letters Patent. Patented May 25, 1915.

Application filed September 26, 1913. Serial No. 791,751.

To all whom it may concern:

Be it known that I, WILLIAM R. McCULLA, a subject of the King of Great Britain, and resident of Detroit, Wayne county, State of Michigan, have invented certain new and useful Improvements in Mufflers, of which the following is a specification.

This invention relates to mufflers and particularly to mufflers for use with hydrocarbon motors having a plurality, or a plurality of sets, of cylinders.

Mufflers built according to this invention are particularly useful with 6-cylinder motor vehicle motors wherein the exhaust of the various cylinders overlap each other. In this case the exhaust from the three forward cylinders is led to the muffler through one pipe and the exhaust from the three rearward cylinders is led to the muffler through another pipe, and the present muffler is designed to continue the separation of the exhaust from the separate sets of cylinders, until it is discharged into the atmosphere.

One of the objects of the invention, therefore, is to provide a double muffler within a single casing.

Another object of the invention is to provide a muffler having a pair of inlet openings and a pair of corresponding outlet openings and independent muffling passages within the casing connecting the respective inlets and outlets.

Other objects of the invention will be apparent from the following description taken in connection with the drawings which form a part of this specification, and in which—

Figure 1 is a part elevation and part sectional view of a muffler built according to this invention; Fig. 2 is a rear end view of the muffler shown in Fig. 1; and Fig. 3 is a transverse section approximately on the line 3 of Fig. 1.

Referring to the drawings, 10 represents the outer cylindrical casing, and 11 are the end plates, of the muffler. The casing 10 is preferably of sheet metal and is shown as lined with an asbestos-lining 12 which protects the surrounding parts of the vehicle upon which the muffler may be mounted. The end plates 11 are secured together with the casing 10 between them by means of three tie rods 13. Brackets 14 may also be secured to the end plates 11 as shown at the right in Fig. 1.

The muffler is provided with a pair of inlet openings or pipes indicated at 15 and 16 in Fig. 1, these openings entering the forward end 11 of the muffler. The other or rear end of the muffler is provided with a pair of outlet openings or pipes 17 and 18 respectively.

The muffler is divided into two distinct and independent compartments 19 and 20, by means of an imperforate partition or dividing wall 21 which extends longitudinally through the center of the muffler and is secured as by rivets 22 to the muffler casing.

In the respective compartments, 19 and 20, are tubular members 23 and 24 which extend longitudinally of the muffler and are provided with a series of perforations adjacent their forward ends. These tubular members 23 and 24 form continuations of the respective inlet pipes 15 and 16 and therefore receive the exhaust gases directly from these inlet pipes. Surrounding the tubular members 23 and 24 respectively, are tubular members 25 and 26 which are of somewhat irregular cross section and considerably larger than the tubular member 23 and 24. These larger tubular members are shown as perforated adjacent their rearward ends and it will be understood that the exhaust gases will pass from the small tubular members through the perforations into the larger tubular members and from thence through the perforations thereof to the compartments 19 and 20. The exhaust gases in the compartments then escape through the respective outlet openings or pipes 17 and 18. By this arrangement of pipes and tubes, the exhaust gases which enter the muffler through the inlet pipe 15 are broken up in the muffler and exploded through the outlet pipe 17 and are entirely independent at all times of the gases in the other side of the muffler.

Upon reference to Fig. 3 in particular, it will be seen that the tubes and pipes of the muffler are symmetrically arranged therein which insures uniformity of action by both sides of the muffler and also assists in making the muffler easier to manufacture.

A specific embodiment of the invention has been described in detail and will be specifically claimed, but it will be understood that the invention is not limited to the exact details of the construction shown, as

it will be apparent that changes may be made without departing from the spirit or scope of the invention.

Having thus described my invention, what I claim and desire to secure by Letters Patent is:

1. A muffler comprising a casing having an imperforate dividing wall therein, and independent exhaust passages in said casing, separated by said wall.
2. A muffler comprising a casing having an imperforate dividing wall therein, and symmetrical exhaust passages on opposite sides of said wall.
3. A muffler comprising a casing having an imperforate dividing wall therein, and symmetrical independent exhaust passages on opposite sides of said wall.
4. A muffler comprising a cylindrical casing having a dividing wall therein separating said casing into semi-cylindrical compartments, and symmetrical exhaust passages in said compartments.
5. A muffler comprising a cylindrical casing having an imperforate dividing wall therein, and a plurality of inlet and outlet passages for exhaust gas, the respective inlets and outlets being separated by said dividing wall.
6. A muffler comprising a casing having two independent inlets and corresponding outlets, and muffling passages within the casing connecting the respective inlets and outlets, the passages from one inlet to its cor-

responding outlet being independent of the other passages.

7. A muffler comprising a cylindrical casing and ends having a pair of inlet openings and corresponding outlet openings, a longitudinal partition in said casing dividing it into two compartments, a perforated tubular member in each compartment communicating with its respective inlet opening, and a second perforated tubular member in each compartment surrounding the first tubular members respectively, said outlet openings communicating with the compartments respectively.

8. A muffler comprising a cylindrical casing and ends having a pair of inlet openings and corresponding outlet openings, a longitudinal partition in said casing dividing it into two compartments, a perforated tubular member in each compartment communicating with its respective inlet opening, and a second perforated tubular member of irregular cross section in each compartment surrounding and somewhat larger than the first tubular members respectively, said outlet openings communicating with the compartments respectively.

In testimony whereof I affix my signature in the presence of two witnesses:

WILLIAM R. McCULLA.
